UNITED STATES PATENT OFFICE.

LOENDER C. EMERSON, OF NORTH GRAFTON, MASSACHUSETTS, ASSIGNOR
OF ONE-HALF TO CHARLES H. NELSON, OF SAME PLACE.

EYELETING-MACHINE.

SPECIFICATION forming part of Letters Patent No. 368,140, dated August 9, 1887.

Application filed December 2, 1886. Serial No. 220,470. (No model.)

To all whom it may concern:

Be it known that I, LOENDER C. EMERSON, a citizen of the United States, residing at North Grafton, in the county of Worcester and State of Massachusetts, have invented certain new and useful Improvements in Eyeletting-Machines, of which the following is a specification, reference being had therein to the accompanying drawings.

10 My invention relates to that class of eyeletting-machines which punch the holes for the eyelets, automatically feed the eyelets to the holes made for them and set them therein, and automatically feed the work along as the eyelets are set; and the principal object of my invention is to produce an improved machine of the class referred to, capable of being controlled by the operator, so that without stopping the machine the operation of the eyelet feeding and setting mechanism may be suspended at pleasure to punch holes in the work without setting eyelets therein. If desired, the feed of the machine may be increased by the same movement by which the operation of the eyelet feeding and setting mechanism is suspended, and thus the holes in which no eyelets are set will be farther apart in the work than the eyeleted holes. My machine is thus adapted for eyeleting that class of boot or shoe work having lacing-studs as well as eyelets, the holes punched for the lacing studs being preferably a greater distance apart than the eyeleted holes.

30

In the class of machines to which my invention relates the work has heretofore been fed by a horizontally-moving finger, forming a part of the eyelet-setting mechanism; but this manner of feeding the work is objectionable, particularly with thin goods, as the work is more or less strained and stretched, and such machines are therefore not adapted for eyeleting thin textile fabrics. In my improved machine I have provided an independent feeding mechanism, consisting, preferably, of two rocking segments, between which the work is clamped in feeding, so that the thinnest fabrics may be fed without injury. The length of the feed may be adjusted as may be desired, or the feed may be suspended altogether, to adapt the machine for eyeleting calendars, &c., where only a single eyelet is set in each piece

of work, and when an automatic feeding of the work is not required.

In the drawings, Figures 1 and 2 are elevations from opposite sides of my improved machine. Fig. 3 is a front end view thereof. Fig. 4 is a central longitudinal section through the lower part of the machine. Fig. 5 is a detail view of the cam for operating the slide or carriage carrying the punch-block and the lower set. Fig. 6 is a cross section through the upper part of the machine on the line 6-6, Fig. 1, looking in the direction of the arrows adjacent to said line. Fig. 7 is a rear end view of the upper part of the machine, with the frame partly in section. Fig. 8 is an enlarged detail section of the feeding-finger and upper set. Fig. 9 is a detail perspective view of the lower or delivery end of the eyelet-chute. Fig. 10 is a detail perspective view of the feeding-sectors. Fig. 11 is a sectional view of the bearing or hanger for the shaft of the upper feeding-sector and adjacent parts. Fig. 12 is a detail sectional view showing the prime feed-operating shaft, its actuating-cam, and adjacent parts. Figs. 13 and 14 illustrate a modified form of feeding mechanism. Figs. 1 and 2 are on a somewhat smaller scale than the other figures excepting Fig. 8.

A denotes the frame of the machine, and B the main or driving shaft, having a driving-pulley, b, mounted loosely thereon, but connected therewith by means of the spring-acted dog b', pivoted to a collar, b², fast on said shaft, said dog being normally forced into engagement with a notch in a flange, b³, of the wheel b by a coil-spring, b⁴, seated in a recess in said collar. (See Fig. 4.)

C is a rock-shaft mounted in the lower part of the frame A, and provided at one end with a tripping-arm, c, adapted to disengage the dog b' from the notched flange of the wheel b, said shaft having also an arm, c', which is to be connected with a suitable treadle to operate the shaft C, for the purpose of disengaging the clutching-dog b' from the wheel b, and thus stop the machine. This clutching mechanism is, however, of itself old and not of my invention.

Journalled in the lower part of the frame A, in line with the driving-shaft B, is a secondary shaft, D, having a clutch-connection with said

driving-shaft, as will be described hereinafter. The punching and feeding mechanism are operated from the driving-shaft B, while the eyelet feeding and setting mechanisms are operated from the secondary shaft D, so that when the shaft D is disconnected from the shaft B the operation of the eyelet mechanisms, which I will now first describe, will be suspended.

E is a slide or carriage having dovetailed flanges e, by which it is guided in ways formed by the under cut plates a, secured to the front end of the lower part of the frame A, said slide or carriage having a standard, E', through which slides vertically the bar e', carrying the setting-finger or lower set, e². To the said standard is attached a post, 10, carrying the punch block 11. The slide E is reciprocated horizontally by means of a rock-shaft, F, having at its rear end an arm, f, provided with a pin or roller engaging a cam-groove, g, in the disk G, secured to the shaft D, the said rock-shaft F having at its forward end a slotted arm, f', engaging an adjustable bolt, e³, attached to the slide E. By adjusting the bolt e³ so that it will be nearer to or farther from the center of movement of the shaft F the throw of the slide E may be varied as desired.

To the sliding bar e' is attached a collar, e⁴, which is connected by a link or pitman, e⁵, 30 with the crank-disk d at the forward end of the shaft D, so that as the said shaft rotates the said bar will be reciprocated vertically to cause the set carried thereby to co-operate with the upper set in setting the eyelets.

H is a rock-shaft journaled in lugs or hangers a², formed on the upper part of the frame A, said shaft having at its rear end an arm, h, connected by a pitman, h', with an eccentric, H', carried by the shaft D. At the forward end of the shaft H is an arm, h¹⁰, connected by a link, h², with a bar, h³, sliding vertically in bearings formed in flanges i of a head, I, pivotally attached by a screw-bolt, i', to the forward end of the upper part of the frame A. 45 The sliding bar h³ carries the upper set, h⁴, which is in the present instance adjustably attached to the said bar by the fastening-screw h⁵, the said set being guided by the lower flange of the head I, so that it will move steadily with the said head as the latter swings.

J is a stationary eyelet-box having a stationary roadway or chute, j, down which the eyelets pass to the eyelet-feeding finger h⁶, which reciprocates vertically in the upper-set, 50 h⁴. The said finger h⁶ is provided near its lower end with a friction-spring, h⁷, (see enlarged detail view, Fig. 8,) which serves to retain the eyelets thereon while the said finger is moving from the lower end of the stationary eyelet-chute j (which is above the work-plate) to the holes in the work into which the eyelets are to be inserted. The feeding-finger h⁶ is retained in the upper set, h⁴, by a friction-spring, h⁸, pressing against the shank of said finger, 55 (see Fig. 8,) the latter being forced outward from the said set as the latter rises by a rod, i², attached by a screw to a pin or stud, i³, fast

in the swinging head I. Thus, as the upper set rises, the finger h⁶ will be protruded therefrom, owing to the contact of the upper end of its shank with the rod i². The swinging movement of the head I will next bring the said finger over the delivery end of the chute j, and before the said head commences its return movement the bar h³ will have descended far enough to cause the said finger to take an eyelet from the lower end of the chute, and the continued movement of the said head brings the eyelet-finger and upper set over the hole in the work, into which the eyelet is inserted as the upper set and eyelet-finger descend, the lower set being at this time beneath said hole. The contact of the eyelet-finger with the lower set forces said finger up into the upper set, where it is retained by the spring h⁹ until again forced outward by the rod i². The eyelet-chute j is provided at its lower end with a retaining-spring, j', which extends partly across the delivery-notch j², but which yields to allow the eyelets to be taken out of the said chute by the eyelet-feeding finger h⁶. The eyelet-box has within it an ordinary agitating-brush, operated in the usual manner from the arm h¹⁰ on the rock-shaft H, said arm being connected by a link, j³, to the arm of the brush-shaft.

The swinging head I is operated in one direction by a rock-shaft, K, having at its forward end an arm, k, carrying a pin or roller engaging a grooved block, i⁴, on the head I, or to a plate attached thereto. The shaft K is provided at its rear end with an arm, K', having a roller-stud, k², which at proper intervals is engaged by a cam or tappet, h¹¹, secured to the shaft H. The return movements of the head I and of the rock-shaft K are effected by a coil-spring, L, attached to said head and to a block or projection, a⁵, on the frame A. An adjustable screw-stop, a⁶, tapped in the block a⁵, limits the return movements of the head I. To prevent the said head from overthrowing I also prefer to employ a stop-screw, a⁷, tapped in a block or projection, a⁸, on the frame A. The punch 12 is carried by a vertically-reciprocating bar, 13, having bearings in the flanges i of the swinging head I, the said punch being steadied by passing through the lower one of the said flanges, as is the upper set, h⁴. The bar 13 is connected by a link, 14, with an arm, 15, on the forward end of a rock-shaft, 16, the rear end, 17, of which is connected by a pitman, 18, with the strap 19 of an eccentric, 20, fast on the driving-shaft B, so that as the said shaft rotates the punch will be reciprocated to perform its work.

The feeding mechanism which I prefer to employ consists of two oscillating sectors, M and M', between which the work is clamped during the feeding movement, the upper sector rising to unclamp the work when the sectors swing backward, the said sectors being slotted to embrace the work on both sides of the punching and eyeleting devices, which can work through the slots of the sectors.

The upper sector, M, is formed on an arm, m , of a stud or small rock-shaft, m' , journaled in a hanger or bearing, o , carried by a vertically-movable bar, O, extending through the upper part of the frame A and having near its top a pin, o' , engaged by lifting-lever Q. The shaft m' is provided at its rear end with an arm, m^2 , connected by a link, m^3 , with an arm, n , of a rock-shaft, N, having at its rear a second arm, n' , connected by a pitman, n^2 , with an arm, p , of a short rock-shaft or stud, P, having within the frame A an arm, p' carrying a roller-stud engaging the grooved cam R on the driving-shaft B. The lower sector, M', is carried by the arm s of a rock-shaft, S, the forward end of which is journaled in a standard, T, to which is attached the work-plate t, the arm s' on the rear end of said shaft S being connected by a link, s^2 , with an arm, n^3 , on the rock-shaft N, from which the upper sector, M, is operated, and thus the sectors will be caused to move in unison. The lever Q, by which the bar O is lifted to raise the sector M and unclamp the work, is connected at its rear end with the pitman 18 by a rod, q, having adjusting and set nuts q' and q^2 , and the downward movements of the said bar and the parts supported thereby are effected by a spring, V, pressing on the bearing o, the latter being provided with a stud, o^2 , entering a hole in the frame A and serving to prevent torsional movement of the bar O.

The pitman n^2 is preferably made adjustable in length by being formed in two parts, the adjacent ends of which are threaded to fit within a right and left hand threaded sleeve, n^8 , which may be turned to lengthen or shorten the said pitman. The latter is jointed at its upper end to a loop, n^4 , adapted to slide on the arm n of the rock-shaft N, the said loop being held between adjustable collars n^5 , the position of which on the arm n' may be changed to vary the point of connection (through the loop n^4) of the pitman n^2 with the said arm n' to vary the rocking movement of the said shaft N, and thus adjust the normal throw of the feeding-sectors operated therefrom. The pitman n^2 is also provided at its lower end with a jointed loop or collar, n^6 , adapted to slide on the arm p of the stud or rock-shaft P, the said loop n^6 being connected by a link, w , with an arm, w^4 , carried by a collar, w' , on a rock-shaft, W, and the said shaft being provided with an ordinary forked arm, w^2 , engaging a sliding collar, X, splined to the driving shaft B. The eccentric H', which is on the shaft D, is provided with a pin, 21, adapted to fit a hole in the sliding collar X, so that the driving-shaft B and the secondary shaft D may be connected or disconnected by moving the said collar into or out of engagement with the said pin, the latter and the collar with the hole to receive said pin thus forming a clutch by which the shafts B and D may be coupled together. The collar w' is provided with a second arm, w^3 , which will in practice be connected with a suitable treadle to operate the clutch fork or arm w^2 .

As the loop n^6 is connected by the link w , arm w^4 , and collar w' with the rock-shaft W the movement of the latter in unclutching the 70 secondary shaft D (from which the eyelet feeding and setting mechanisms are operated) from the driving-shaft B will cause the said loop to slide outward on the arm of the prime feed-operating rock-shaft P, and thus a greater reciprocating movement will be imparted to the pitman n^2 to give an increased rocking movement to the shaft N, and also the rock-shaft S connected therewith, so that the movement of the rock-shaft W in unclutching or disconnecting the secondary shaft from the driving-shaft to suspend the operation of the eyelet feeding and setting mechanisms will also give an increased throw to the feeding-sectors, and thus space the non-eyeleted holes farther apart than 85 the eyeleted ones.

The outward movement of the loop n^6 at the lower end of the pitman n^2 on the arm p of the rock-shaft P is limited by an adjustable stop, consisting in the present instance of a collar, p^2 , Fig. 2, held in place on said arm by a set-screw.

When my machine is set in motion, its operation is as follows: The punch 12, receiving its motion from the rock-shaft 15, operatively 95 connected with the eccentric 20 in the driving-shaft B, first descends and makes a hole in the work, the punch-block 11 being at this moment beneath the punch. As the punch rises, the punch-block, carried by the slide or 100 carriage E, moves backward or to the right, Fig. 3, thus removing the punch-block from beneath the hole which has been made in the work and bringing the lower set, e^2 , beneath the said hole. The punch as it rises is (owing 105 to the swinging of the head I, in which it has vertical bearings) carried to the left, Fig. 3, this movement of the said head bringing the descending upper set, h^4 , in a vertical line with the hole in the material and the lower set, e^2 . 110 During the downward and forward movement of the upper set, h^4 , the eyelet-feeding finger h^6 carried thereby has taken an eyelet from the eyelet-chute, and as the upper set continues its downward movement (the lower set meanwhile rising) the eyelet is inserted in the hole made for it by the punch and properly set, the eyelet-feeding finger being forced within the set h^4 during the setting operation and protruded therefrom, when the set again rises by 115 the rod r on the head I, as hereinbefore described. As the upper set rises, the return movement of the swinging head I carries it backward (or to the right, Fig. 3,) thus bringing the punch to its first position, the slide or carriage 120 E at the same time moving forward, (or to the left, Fig. 3,) to carry the lower set (which has meanwhile descended) away from beneath the punch and to bring the punch-block back again into operative position. After the two 125 sets have been withdrawn from the work and before the punch again reaches it, the feeding-sectors M and M', between which the work is now clamped, and which are operated by the

mechanism hereinbefore described, swing to feed the work forward (or to the left, Fig. 3,) and as the punch reaches the work the upper sector, M, is raised through the operation of the 5 lifting-lever Q, to release the work, and while the work is thus unclamped the feeding-sectors are swung backward to their first position.

The movements above described are repeated during the usual operation of the machine in punching holes and setting eyelets therein; but when the proper number of eyelets have been set in a shoe-counter, and it is desired, without stopping the machine, to 10 punch a series of holes for studs and to space the said holes farther apart than the eyeleted holes, the operator presses down on a treadle which is to be connected with the arm w', rigidly connected with the clutch-operating rock-shaft W, to slide the collar X rearward, and thus uncouple the secondary shaft D, by which the eyelet feeding and setting mechanism, the 15 sliding carriage E, and the swinging head I are operated, from the driving-shaft B, from which the punching and feeding mechanisms 20 receive their movements, and thus the latter mechanisms will continue their operation to make properly-spaced holes in which no eyelets will be inserted. Owing to the connection 25 by the link w of the loop n⁶ at the lower end of the feed-operating pitman n⁷ to the arm w', moving with the clutch-operating rock-shaft W, the lower end of the said pitman will be moved outward relative to the arm p of the 30 prime feed-operating shaft P simultaneously 35 with the uncoupling of the shafts D and B, to increase the feed when the holes in which no eyelets are to be inserted are being punched, as hereinbefore described, this movement of 40 the lower end of the said pitman being reversed to restore the normal feed when the 45 said shafts are again coupled together to resume the eyeleting operations.

It will be observed that the lower end of the 50 eyelet-chute j is above the work-plate t, and owing to the form of said chute the eyelets, when they reach the lower end thereof, have their flanged or finished ends upward, so that the eyeleting operation is performed with the 55 "right" or outer side of the work upward. This enables the operator to inspect the work as the eyeleting and punching operations proceed and to see if there are any bad places 60 therein, and my machine will therefore be found more convenient in use than the "combination" eyeleting-machines heretofore extensively employed. The retaining-spring h⁸, near the end of the eyelet-feeding finger h⁹, is an important feature of my invention in carrying 65 the eyelets from the stationary chute to the holes in the work punched for their reception and inserting them in the holes from above the work. When the operation of the eyelet feeding and setting devices are suspended, the sliding movements of the carriage E and the swinging movements of the head I are also suspended, these movements being

imparted to the said slide and carriage from the rock-shafts F and K, operated from the secondary shaft D, as hereinbefore described, 70 so that when the punching operation goes on without the eyeleting operation the punch-block remains stationary beneath the punch, and the latter merely reciprocates vertically in the head I, which latter remains at rest until the eyeleting operation is resumed. 75

If it be desired to punch holes alone or to punch eyelet-holes in work where no feed is necessary, owing to the fact that only a single hole or eyelet is required in each piece, as in eyeleting calendars, &c., the feeding devices 80 may be disconnected from their operating mechanism, as by removing the pitman n⁷; or the said pitman may be adjusted on the arm n' so closely to the center of movement of the 85 shaft N that little or no movement will be imparted to the said shaft, and thus the feeding-sectors operated therefrom will be entirely or practically at rest. When the feed is thus suspended, the sector M may be raised so as to 90 be clear of the work by an ordinary lifting-lever engaging the bar O or the lever Q, and, if desired, the feed may be suspended simply by raising the upper sector from the work and retaining it in such position; but power will 95 be saved by disconnecting the rod n².

By employing an independent feeding mechanism, or a feeding mechanism which operates independently of the eyelet-setting devices, my machine is adapted for setting 100 eyelets in thin materials, which are more or less injured when fed by the setting devices, as in the forms of eyeleting-machines now in use. As hereinbefore stated, I prefer to use the slotted swinging sectors, as described; but 105 other feeding mechanisms may obviously be employed—such as, for example, are shown by Figs. 13 and 14—such mechanism consisting of two feeding-wheels, M² and M³, the shaft m' of the upper wheel, M², being intermittently 110 rotated by the ratchet-wheel m⁴, operated by the pawl m⁵, pivoted to the carrier m⁶, operated from the rock-shaft N through the link m⁷ and arm n, the lower wheel, M, rotating idly by the movement of the work between it 115 and the upper wheel. These feeding-wheels are in a certain sense the equivalents of the feeding-sectors M M', in that they afford two coincidently-moving surfaces between which the work is clamped in feeding. 120

I do not, therefore, wish to be understood as limiting my invention to the specific operating mechanisms hereinbefore described, as it is obvious that the details of my machine may be varied within the limits of mechanical skill 125 without departing from the leading features thereof.

The peculiar arrangement of the mechanism of my machine enables me to provide a much greater amount of room under the arm or back 130 of the punch and sets than there is in similar machines heretofore in use, so that my machine is adapted for a much larger range of work than the old machines.

Having thus described my invention, I claim and desire to secure by Letters Patent—

1. In an eyeleting-machine, the combination, with the eyelet setting devices and a shaft 5 with which they are operatively connected, of feeding appliances consisting of two moving parts between which the work is clamped in feeding, substantially as described, and a shaft separate from the aforesaid shaft with which 10 the said feeding appliances are operatively connected.

2. In an eyeleting-machine, the combination, with the punching and eyelet-setting devices and their operating mechanism, of an 15 independent feed consisting of two swinging sectors between which the work is clamped in feeding.

3. In an eyeleting-machine, the combination, with the punching and eyelet-setting devices, of a feeding mechanism consisting of two swinging sectors slotted to embrace the work 20 on both sides of the line of the eyelets and to permit the said punching and setting devices to work between or inside of the work-clamping 25 portions of the said feeding sectors.

4. In an eyeleting-machine, the combination, with punching and feeding devices and a driving-shaft with which they are operatively connected, of a secondary shaft, eyelet feeding 30 and setting appliances operatively connected with the said secondary shaft, and a clutch for connecting and disconnecting said shafts.

5. In an eyeleting-machine, the combination, with a horizontally-reciprocating slide or 35 carriage below the work-plate and the lower set and punch-block carried thereby, of a swinging head above the work-plate, and the vertically-reciprocating upper set and punch and their carrying-bars guided in the said head.

40 6. In an eyeleting-machine, the combination, with the upper and lower eyelet sets and an eyelet roadway or chute, of an eyelet-feeding finger movable lengthwise in one of the said sets, a friction-spring for holding said finger stationary in said set at intervals, and a rod for causing said finger to protrude from the set when the said finger is to take an eyelet from the said roadway or chute.

7. In an eyeleting-machine, the combination, 45 with the work-plate and a stationary eyelet roadway or chute the delivery end of which is above said plate, of a swinging eyelet-feeding finger provided near its lower end with an eyelet-retaining spring.

50 8. In an eyeleting-machine, the combination, with the upper feeding-sector and the rock-shaft N, with which said sector is operatively connected, of the lower feeding-sector and its rock-shaft S, connected with the rock-shaft N, whereby the said sectors are caused to move in unison in feeding the work.

9. The combination, with the upper feeding-sector, M, its arm m, and the stud or rock-shaft m', of the bearing o, the vertically-movable bar O, by which said bearing is carried, 55 the spring V, the lifting-lever Q, for raising

said sector at intervals, and a reciprocating device, as rod q, for operating said lever.

10. The combination, with the feeding-sector M, its arm m, and the stud or rock-shaft m', of the vertically-movable bar O, and the bearing o, carried by said bar and provided with the steadyng-stud o², for preventing torsional movement of the bar O.

11. The combination, with the feeding-sectors M and M', and the rock-shafts N and S, operatively connected together and to the said sectors, of the prime feed-operating shaft or stud P, connected with the shaft N, the cam R, and driving-shaft B, to which the said cam is attached.

12. The combination, with the driving-shaft B, of the cam R, the stud or rock-shaft P and its arms, the pitman n² and its pivoted loops, the three-armed rock-shaft N, the stud or rock-shaft m' and its bearing, the link m', the sectors M and M', the rock-shaft S and its arms, and the link s', connecting the arms of the rock-shafts N and S.

13. The combination, with the slide or carriage E, the lower set, its reciprocating carrying-bar, and the punch-block and its post, of the two-armed rock-shaft F, the cam-grooved disk by which the said shaft is operated, and the shaft D, by which the said disk is carried.

14. The combination, with the punch, its carrying-bar and the head in which the latter is guided vertically, of the two-armed rock-shaft 90 16, the links or pitmen 15 and 18, eccentric 20 and its strap, and the driving-shaft B.

15. The upper and lower sets and their carrying-bars, combined with the rock-shaft H and its arms, the links or pitmen h' h', the eccentric H', the shaft D, having a crank at its 100 forward end, and the link e', connecting said crank to the reciprocating bar e'', by which the lower set is carried.

16. The combination, with the pivoted head I and the carrying-bars for the punch and upper set guided vertically therein, of the two-armed rock-shaft K, for operating said head, the rear arm of the said shaft having a stud or roller, the rock-shaft H, having a cam or tappet, h¹¹, and the retracting-spring L.

17. In an eyeleting-machine, the combination, with a driving-shaft and punching and feeding mechanisms operated thereby, of a secondary shaft, eyelet feeding and setting devices operated by said secondary shaft, a clutch connecting said shafts, and a clutch-operating device connected with the feeding mechanism, whereby when the said clutch is uncoupled to disconnect said shafts and suspend the operation of the eyelet feeding and setting devices the feed will be increased.

18. The combination, with the driving-shaft B and the punching and feeding mechanisms operated thereby, of the secondary shaft D, the eyelet feeding and setting appliances operated by said shaft D, the clutch connecting said shafts, the clutch-operating shaft W, its

arms w^2 and w^4 , the feed-operating stud or shaft P, its arm p, a sliding loop or collar thereon, the link w_1 and the pitmen n^2 , forming a part of the said feeding mechanism and 5 to which said collar is connected, whereby when the clutch is uncoupled to disconnect the secondary shaft from the driving-shaft the said loop or collar will be moved outward on the said arm to increase the feed of the work.

10 19. The combination, with feeding devices and the feed-operating rock-shaft N, connected therewith and having an arm, n' , of the ad-

justable collars n^5 , and the pitmen n^2 , having a loop or portion fitting the said arm and held in any desired position by the said collars, 15 whereby the feed may be changed when necessary.

In testimony whereof I affix my signature in presence of two witnesses.

LOENDER C. EMERSON.
